(57) **CLAIM**

The ornamental design for a power controller contactor cover, as shown and described.

DESCRIPTION

FIG. 1 is a perspective view of the power controller contactor cover showing our new design;

FIG. 2 is a front view thereof; and,

FIG. 3 is a side view thereof.

The broken lines are included for the purpose of illustrating environmental structure and form no part of the claimed design.

1 Claim, 3 Drawing Sheets

FIG. 1

FIG. 2

FIG. 3
